(57) **CLAIM**

The ornamental design for a wrist watch, as shown and described.

DESCRIPTION

FIG. 1 is an upper perspective view of the wrist watch showing our new design;

FIG. 2 is a top plan view thereof;

FIG. 3 is a bottom plan view thereof;

FIG. 4 is a front elevation view thereof;

FIG. 5 is a side elevation view thereof;

FIG. 6 is an opposite side elevation view thereof; and,

FIG. 7 is a lower perspective view thereof.

The features presented in broken lines are for environmental purposes only and form no part of the claimed design.
